UNITED STATES PATENT OFFICE.

ARCHIBALD S. CUBITT, OF SCHENECTADY, NEW YORK, ASSIGNOR TO GENERAL ELECTRIC COMPANY, A CORPORATION OF NEW YORK.

THROTTLE-RELAY.

No. 873,729.

Specification of Letters Patent.

Patented Dec. 17, 1907

Application filed March 31, 1906, Serial No. 309,124.

To all whom it may concern:

Be it known that I, ARCHIBALD S. CUBITT, a subject of the King of Great Britain, residing at Schenectady, county of Schenectady, 5 State of New York, have invented certain new and useful Improvements in Throttle-Relays, of which the following is a specification.

The present invention relates to current 10 relays and more particularly relays adapted to govern circuit-controlling devices in order to prevent the circuit conditions from becoming abnormal. In motor control systems for example, controlling devices of some sort 15 are used for decreasing resistance of the motor circuit or otherwise gradually changing the circuit conditions in accelerating the motor so as to bring it from rest up to speed. It is common to provide means controlled by 20 the motor current for preventing the controlling device from being carelessly operated so as to subject the motor to too great a rush of current. A satisfactory arrangement consists in a locking device for the controller 25 which locking device is in turn governed by a relay having its windings in the motor circuit; and, in order to make this relay as small as possible and still secure considerable torque, the movable member of the relay 30 usually comprises an iron plunger. The presence of the iron core or plunger, however, makes the relay less sensitive, since a much larger current is required to lift the plunger than to maintain it lifted. Therefore, if the 35 parts are so proportioned that the relay operates to cause the controller to be locked when the motor current reaches a predetermined value, unlocking of the controller does not take place until the current has fallen 40 materially below that value, namely, below a value which is entirely safe.

The object of the present invention is to make a relay of the character described more sensitive so that it will open and close within 45 narrower limits of current value than heretofore.

To the above end the present invention contemplates the use of an auxiliary winding on the relay so arranged as to compensate 50 for the difference in pull required to lift the plunger and to maintain it in its lifted position. This coil may either be arranged so as to normally assist the main coil and to be cut out when the relay has operated, or the auxiliary coil may be one which is normally idle

but which, after the relay has been operated, becomes energized and opposes the action of the main winding. In this way the effective pull upon the plunger immediately decreases upon the operation of the relay, so that the 60 plunger of the relay may drop upon a much smaller decrease in the motor current than would be the case without the auxiliary winding.

The present invention will be more clearly 65 understood from the following detailed description taken in connection with the accompanying drawing wherein

Figure 1 shows diagrammatically a motor controlled system having a throttle relay arranged in accordance with the present invention; Fig. 2 is a front elevation of the throttle relay; Fig. 3 is a longitudinal cross-section of the relay; and Fig. 4 shows diagrammatically a further modification of relay. 70

Referring to Fig. 1: M is a motor, R¹, R² and R³ are resistance sections adapted to be introduced into the motor circuit and eliminated therefrom in accelerating; C is a motor controller of the separately-actuated 75 contact type adapted to connect the motor to a source of current supply and to control the resistances; K is a master controller for governing the operation of the motor controller; K¹ is a locking device for the master controller; and A is a relay constructed in accordance with the present invention for controlling the locking device. All these parts, with the exception of the relay, may be of any usual or preferred types, more than one 80 motor may be used, and the method of changing the circuit conditions to vary the speed of the motor may be any of the methods commonly employed for this purpose. 90

The relay A consists of a plunger 1 carrying contact members 2 and 3 adapted to bridge fixed contacts 4 and 5. This plunger is adapted to move within a coil 6 arranged in the motor circuit and a second coil 7 which may conveniently be situated in the 100 control circuit. The contacts 2 and 4, when the relay is in its normal position, break the circuit of the coil 8 of the locking device; while the contacts 3 and 5, when the relay is in the same position, opens a shunt about 105 the coil 7. The coils 6 and 7 are wound so as to assist each other in lifting the plunger. Thus, when the circuit conditions are such that the plunger of the relay is lifted, the 110 closing of the contacts 2 and 4 completes the

circuit of the lock coil 8 and the contacts 3 and 5 complete the short-circuit about the coil 7. As soon as the coil 7 is short-circuited the influence of this coil is eliminated and 5 the plunger is maintained raised solely through the action of the coil 6. It is evident that the coils 6 and 7 may be so proportioned that the plunger will drop again after the current in the motor circuit has decreased to any desired value below the value 10 which is required for the operation of the relay.

The operation of the particular system illustrated is as follows: When the controller 15 is turned to the first running position, current flows from one terminal 9 of the source of supply, through contacts 10, 11, 12 and 13 of the master controller, through the actuating coils of line switches T^2 , T^1 and T , through 20 the coil 7, to ground, namely to the opposite terminal of the source of supply. The motor circuit is now from terminal 9, through switches T , T^1 , T^2 , through resistances R^1 , R^2 and R^3 , through the coil 6 of the relay, 25 through the motor, to ground. In the second position of the master controller contact 14 engages with contact 15 and switch r^1 , governing resistance section R^1 is closed. Thus resistance section R^1 is short-circuited 30 and the current to the motor increased. If the short-circuiting of the resistance section causes the motor current to rise above a predetermined value, the combined action of the coils 6 and 7 lifts the plunger of the relay 35 and causes the master controller to be locked against further forward movement until the motor current has again fallen to a second predetermined value. In the same way, in the third and fourth positions of the controller, 40 the switches r^2 and r^3 are closed and resistance sections R^2 and R^3 are short-circuited, and the relay and controller locking device operate in the manner described to lock the controller against further movement when 45 in either of these positions of the controller the motor current rises beyond the value desired.

In Figs. 2 and 3 I have illustrated the actual construction of the relay A. The coils 50 6 and 7 are preferably supported within a U-shaped frame 16 which, together with a plug 17 and the plunger 1, make a complete magnetic circuit for the coils when the plunger is raised. The contact members 2 and 3 preferably take the form of disks loosely arranged upon the plunger; the disk 2 being supported upon a spring 18 which in turn rests upon a collar 19 fixed to the plunger. The disk 3 rests upon a collar 20 on the plunger and between the upper side of the disk 55 and a collar 21 is arranged a spring 22. This latter disk, together with the fixed contact pieces 5, is made of magnetic material; the pieces 5 being normally magnetized by means of coils 23 surrounding them. Thus

when the plunger rises, the disks engage with their respective fixed contacts; but when the plunger begins to drop, the disk 3 is magnetically held in its raised position in contact with the members 5 until the plunger has 70 left the field of winding 7. Thereupon the plunger strikes the disk a slight blow and the spring 22, which has been compressed during the downward movement of the plunger, quickly throws the disk downward to break 75 contact. It will be seen that by this arrangement the short-circuit about the coil 7 is not broken until the plunger has reached a point at which the effect of the coil 7 is insufficient to cause the plunger to be again 80 lifted before the current through the winding 6 has risen to the desired point.

In Fig. 4 I have shown a modification wherein the contacts 3^a and 5 normally short-circuit the coil 7^a; this coil being wound 85 so as to oppose the coil 6. In this modification the plunger 1^a is lifted entirely through the action of the main coil 6 and the influence of this coil is weakened when the coil 7^a is cut in. In this modification the spring 22^a is arranged beneath the disk 3^a so that the contacts 3^a and 5 are not separated until the plunger has substantially reached its elevated position.

It will be noted that the circuit including 95 coils 7 and 7^a carries currents which vary as the master controller is operated and the effect of these coils may thus be automatically varied. If a constant current is desired in the circuit containing them the coils may be 100 placed in a separate circuit or in circuit with only the switches T T^2 . The particular manner of energizing the auxiliary coils is, however, immaterial as this will differ under different conditions of service. I desire it to 105 be also understood that the throttle relay need not control a lock as indicated but may be employed equally well in place of the throttle relay in an automatic controller such as shown in Patent 763,658, granted on June 110 28, 1904, on an application filed by E. R. Carichoff. Moreover the present invention is applicable to other circuits than motor circuits.

What I claim as new and desire to secure 115 by Letters Patent of the United States, is,—

1. In a system of control, a motor, a controller for varying the motor circuit, a locking device for said controller including a throttle relay having one coil in series with 120 the motor and another coil in shunt to the motor, together with contacts on said relay for controlling the circuit of the coil in shunt to the motor.

2. In a system of control, a motor, a controller for varying the motor circuit, a locking device for the controller including a throttle relay having a coil in series with the motor and an auxiliary coil in shunt to the motor, and contacts on the relay for control- 125 130

ling the circuit of said auxiliary coil, said coils being so proportioned that the cumulative efforts thereof serve to operate the relay upon a predetermined current in the motor circuit.

3. In a system of control, a motor, a controller for varying the motor circuit, a locking device for the controller including a throttle relay having a coil in the motor circuit and an auxiliary coil in shunt to the motor, and contacts on said relay for opening and closing the circuit containing said auxiliary coil, said coils being proportioned and arranged to operate the relay upon a predetermined value of the motor current and the effective pull upon the movable member of the relay to be diminished upon the operation of the relay.

4. In a system of control, a motor, a controller for varying the motor circuit, a locking device for the controller including a throttle relay having a coil in the motor circuit and an auxiliary coil in shunt to the motor, and contacts associated with the relay for deenergizing the auxiliary coil in one of the positions of the relay, said coils being so proportioned and arranged that the relay operates to cause the controller to be locked when the motor current reaches a predetermined value and the effective pull upon the movable member of the relay to be decreased upon the operation of the relay.

5. In a system of control, an electric circuit, means for varying the conditions of said circuit, a device for retarding the operation of said means including a throttle relay adapted to operate when the current in said circuit reaches a predetermined value, and means for weakening the effective holding force of the relay after the relay has operated.

6. In a system of control, an electric circuit, means for varying the conditions of said circuit, a device for retarding the operation of said means including a relay having a plunger which is adapted to be operated when the current in said circuit reaches a

predetermined maximum, and means for decreasing the pull upon the plunger upon the operation of the relay.

7. In a system of control, an electric circuit, means for varying the conditions of said circuit, a device for retarding the operation of said means including a relay having a movable plunger and coil connected in said circuit, an auxiliary coil on said relay, and means associated with said plunger for respectively energizing and deenergizing said auxiliary coil in the two positions of the plunger, the parts being arranged to cause the plunger to be lifted when the current in said circuit reaches a predetermined value and the pull upon the plunger to be weakened upon the operation of the plunger.

8. In a system of control, a motor circuit, a controller for varying the resistance of the motor circuit, means for retarding the operation of the controller including a throttle relay having a plunger adapted to operate when the current in the motor circuit reaches a predetermined maximum, and means for weakening the effective pull upon the plunger after the relay has operated.

9. In a system of control, a motor circuit, a controller for varying the resistance of the motor circuit, means for controlling the operation of said controller including a throttle relay having a movable plunger and main and auxiliary coils, said main coil being in the motor circuit and said auxiliary coil being energized and deenergized respectively in the two positions of the relay, the arrangement being such that the relay plunger is operated when the current in the motor circuit reaches a predetermined maximum and the effective pull upon the plunger is diminished upon the operation thereof.

In witness whereof, I have hereunto set my hand this 30th day of March, 1906.

ARCHIE S. CUBITT.
